UNITED STATES PATENT OFFICE.

IVOR D. THOMAS AND PAUL H. DOUGLAS, OF CLEVELAND HEIGHTS, OHIO, ASSIGNEES
TO THE WELLMAN-SEAVIER-MORGAN COMPANY, OF CLEVELAND, OHIO, A CORPOR-
ATION OF OHIO.

MANIPULATOR.

Application filed April 11, 1921. Serial No. 460,372.

To all whom it may concern:

Be it known that we, IVOR D. THOMAS and PAUL H. DOUGLAS, citizens of the United States, and residents, respectively, of Cleveland Heights, in the county of Cuyahoga and State of Ohio, and Cleveland Heights, in the county of Cuyahoga and State of Ohio, have invented a certain new and useful Improvement in Manipulators, of which 10 the following is a full, clear, and exact description.

This invention relates to manipulators, adapted particularly for manipulating ingots.

15 The principal object of the invention is to provide improved and simplified means for raising and lowering the gripping unit and the parts carried by and movable with it. Further the invention aims to provide 20 improved means for permitting the gripping unit to yield under the action of the forging dies of the press, both vertically and longitudinally so that no undue stresses created by the action of the press will be transmitted 25 to the frame-work of the manipulator.

According to the present invention, the raising or lowering of the gripping unit is accomplished through the medium of a weight or weighted member preferably in 30 the form of a pivoted walking beam. This walking beam is provided with a counterbalance weight which in the preferred construction is movable longitudinally thereof for the purpose of overbalancing the gripping unit, the frame which supports it, and the work carried by the gripping unit, and provision is made for relieving the balanced load produced by the walking beam and its 35 counterweight to permit the lifted parts to be lowered.

40 The invention may be further briefly summarized as consisting in certain novel details of construction, and combinations and arrangements of parts which will be 45 described in the specification and pointed out in the appended claims.

Though the principal features of the invention can be carried out in numerous specifically different ways, and though the 50 invention may be utilized to advantage in a manipulator of the crane type, as well as of the floor type, in the drawings we have shown one embodiment of the invention applied to a manipulator of the floor type, in 55 which Fig. 1 is a side view of the manipu-

lator; Fig. 2 is a diagrammatic plan view of the same on a reduced scale, showing the track upon which the base or lower carriage, in this instance in the form of a turntable, is adapted to travel; Fig. 3 is a vertical sectional view of the principal parts of the manipulator including the carriage which in the embodiment of the invention herein illustrated is movable across the turntable, this carriage carrying the gripping unit and other lifted parts as well as the counterbalancing mechanism, a portion of the latter being broken away; Fig. 4 is a plan view of the carriage of Fig. 3, the same being shown on an enlarged scale, and the 60 forward part of the frame of the carriage being in horizontal section; Fig. 5 is a top plan view of the walking beam and the parts supported by it; Fig. 6 is a longitudinal sectional view of the same; Fig. 7 is a front 65 view of the same, the left half being in section along the line 7—7 of Fig. 6, and the right half in section along the line 7^a—7^a of the same figure; Fig. 8 is a side view of the principal vertically movable 70 parts which at the bottom carry the gripping unit and at the top are adapted to be connected to the walking beam; Fig. 9 is a front view of the top portion of the same; Fig. 10 is a similar view of the bottom portion of the same; and Fig. 11 is a top plan 75 view of the swinging frame in which the manipulator spindle is journaled.

Referring now to the drawings, and first to Figs. 1 and 2, it will be observed that in 80 the embodiment of the invention here shown, the manipulator as a whole includes a carriage in the form of a turntable 10, which is provided with a central pivot bearing 11, shown in Fig. 2, and is adapted to 85 be rotated on a circular track 12, by suitable propelling means with which the turntable will be provided, not here shown in detail, but indicated at 12^a in Fig. 1. The turntable 10 is composed of two end frames 100 13—13, having track wheels 14 adapted to travel on the circular track 12. Likewise the turntable includes two parallel girders 15, extending between the end frames, and provided at the top with rails 16, along 105 which the manipulator proper is adapted to travel.

It is proposed, with the manipulator proper mounted on and movable longitudinally of a carrier in the form of a turntable 110

as here shown, that the ingot heating furnaces and forging press be so located that with the circular movements of the turntable, and with the movement of the manipulator proper, longitudinally thereof, there is a sufficient range of movement for the gripping mechanism to enable the ingot to be picked up at the furnace and conveyed therefrom to the forging press. However, 10 the principal features of the invention are not limited to a manipulator of the floor type, as they may be embodied in a manipulator of the crane type. Furthermore, we wish to make clear the fact 15 that a carrier in the form of a turntable is not a necessary part of the invention, even when applied to a manipulator of the floor type, for the invention would have utility in a manipulator adapted to 20 be supported and arranged to travel otherwise than on movable rails such as here shown provided on the carrier or turntable 10.

What has been referred to as the manipulator proper, includes a carriage composed 25 in part of a frame 17, formed principally of structural material, and provided with wheels 18, which in this instance travel along the rails 16 of the turntable. The 30 carriage propelling means, as shown in Figs. 1 and 4, consists of a motor 19, supported on the frame 17, and geared to a transverse shaft 20, which in turn is geared to short axles carrying two of the track wheels 18 35 (see Fig. 4).

At the front of the frame 17 there is an upright portion 21, having vertical guideways formed by pairs of opposing rails 22 (see Fig. 4) in which is guided for vertical 40 movement a triangularly shaped frame 23 (see Fig. 8) having flanged wheels 24 which engage the guide rails 22. As will be explained subsequently, this frame is connected to and suspended from a pivoted walking beam, shortly to be referred to.

The lower part of this vertically movable frame carries the ingot gripping unit, and in this instance the spindle 25 of the gripping unit (see particularly Fig. 3) is journaled in aligned bearings 26 and 27 of a casting 28, shown in detail in Figs. 8, 10 and 11. This casting is not fixed with reference to the frame 23, but in accordance with an important part of the invention is 50 suspended from the frame by two pairs of parallel links 29, the upper ends of the links being suspended from the frame 23 by being pivotally mounted on cross-pins or shafts 30, and extending down along opposite sides of the casting 28, and at their lower ends being pivotally connected to the lower front and lower rear portions of the casting through the medium of pins 31. These links provide in effect a swinging 60 cradle for the gripping unit, and permit the

latter to yield in an inward or rearward direction as the forging is elongated in the press. This relieves the parts of the manipulator which directly or indirectly support the gripping unit of all stresses incident to 70 the elongation of the ingot.

The gripping unit is provided with the customary appurtenances for gripping, releasing and turning the ingot, and though the details of the gripping mechanism 75 form no part of the present invention, it may be mentioned that the spindle turning mechanism is here shown mounted directly on the casting 28, this mechanism including a motor 32, connected by speed reducing gearing 33 to a gear 34 surrounding and secured to the spindle 25. Furthermore, the spindle will be provided at its forward end with a suitable tong head 35 carrying gripping jaws or tongs 36, adapted to be operated by a shaft 37, extending centrally through the spindle 25, and adapted to be moved endwise of the spindle by an air motor supported at the rear end of the spindle and adapted to be rotated therewith. As 80 shown in Fig. 3, the air motor includes a piston 38 movable back and forth in an air cylinder 39 to which air is supplied by piping 40 from a reservoir 41 on the rear end of the carriage frame 17, and adapted to be supplied with air by a suitable compressor, 85 not shown.

Pivoted to the top of the frame 17 of the manipulator proper, by means of a transverse pin 42, is a walking beam 43, which in this instance is in the form of an elongated or rectangular frame, formed chiefly of structural material. The front end of the walking beam extends over the vertical guideways formed by the rails 22 at the forward portion of the frame 17, and it is connected to the top of the vertically movable frame 23 by a pair of links 44, which at their upper ends are connected to the front end of the walking beam by a cross pin 45, and at their lower ends are connected to the frame 23 by means of a cross pin or shaft 46 on which the two upper vertically movable guide rollers 24 are mounted (see particularly Figs. 8 and 9).

The side portions of the walking beam 43, rearwardly of the pivot pin 42 are provided with tracks 47 along which is adapted to travel a counterweight in the form of a trolley, including a frame or body 48, carrying flanged wheels 49 engaging the tracks 47 of the walking beam.

Provision is made for shifting the counterweight along the walking beam so as to overbalance the vertically movable parts including the gripping mechanism and its load or the ingot, irrespective of the weight of the latter, and provision is made also for rocking the walking beam so as to overcome the unbalanced load produced by the walk- 125

ing beam and its counterweight to enable the gripping unit and ingot to be lowered. These results may be accomplished in different ways and by mechanisms variously 5 mounted and co-ordinated. In this instance, one motor is utilized both for shifting the counterweight to overbalance the vertically movable parts connected to the walking beam, and also for the purpose of lowering 10 the vertically movable parts when once the counterweight has been set at a given point to properly overbalance any particular load, which it is understood, will vary with the 15 weight of the ingot supported by the gripping mechanism, and in this case the motor for these purposes is mounted on the counterweight. However, it is not essential that the result be accomplished by a single motor or that the motor be mounted on the counterweight. Furthermore, we do not desire 20 the invention in its broad aspects to be confined to an adjustable counterweight, for while the counterweight is preferably adjustable or movable on the walking beam for 25 the purpose of conserving power of operation, the counterweight might be stationary, in which event it would be set to overbalance the heaviest load handled.

The motor for shifting the counterweight 30 on the walking beam, and for rocking the walking beam to lower the load supported by it, is shown at 50, the motor being in this instance mounted on an extension 48^a of the counterweight frame or body. This motor 35 is connected by reducing gearing 51 to a shaft 52, indicated by dotted lines in Fig. 6, and this shaft in turn is adapted to be connected by a clutch 53 to a second shaft 54 aligned with it. The front shaft is adapted 40 through the medium of worm and worm wheel gearing 55 enclosed in a case 56, to drive a two-part drum 57 mounted on a shaft 58, and the rear shaft 54 is adapted, through the medium of worm and worm 45 wheel gearing 59 enclosed in a case 60, to drive a two-part drum 61 mounted on a shaft 61^a, both shafts being suitably journaled in the body or frame 48 of the counterweight.

50 Wound in the same direction on the two parts of the drum 57 are two cables 62 which extend from the drums forwardly along the walking beam, and after passing about sheaves 63 on the front cross pin or shaft 45 of the walking beam, these cables extend downwardly and are connected by spring shock absorbers 64 to the relatively fixed upright portion 21 of the frame of the carriage.

55 The two parts of the rear drum 61 accommodate four cables, including two rear cables 64 and two front cables 65. The rear cables 64 are connected to the rear end of the walking beam by spring shock absorbers 66 and 60 extend forwardly and pass one or more times

about the two parts of the drum 61. Similarly the front cables 65 are connected to the front portion of the walking beam by spring shock absorbers 67, and from the latter the cables extend rearwardly along the walking beam and are wound onto the two parts of the rear drum oppositely with respect to the direction in which the rear cables 64 are wound thereon. All cables 62, 64 and 65 are dead-ended on the drums. 70

75 From the above it is obvious that by rotating the two-part drum 57 and the two-part drum 61 in one direction (the clutch 53 then being in) the cables 62 unwind from drum 57, the cables 65 unwind from drum 61, and the cables 64 are wound up on the drum 61. Obviously this moves the counterweight rearwardly along the walking beam. Likewise when the drums 57 and 61 are rotated in the reverse direction the cables 62 are 80 wound up on the drum 57, the cables 64 are unwound from drum 61, and the cables 65 are wound up on the drum 61. This moves the counterweight forwardly along the walking beam. Obviously the drum 61 and the 85 two sets of cables 64 and 65 have the same effect as rack and pinion, or other suitable transmission mechanism for causing the counterweight to travel along the walking beam. This is mentioned for the reason that 90 any such equivalent means may be utilized for shifting the counterweight on the walking beam.

95 It will be obvious also, that when the clutch 53 is out, the effect of the rotation of the motor is to wind in or pay out the cables 62 only. Assuming that the direction of rotation of the motor is such as to wind in on the cables 62, the effect of this 100 is to increase the tension on the cables 62, the result of which is to elevate the rear end and lower the front end of the walking beam, in other words, to lower the load hung from the front end of the walking beam, and therefore to overcome the unbalanced weight of the walking beam and counterweight. Likewise, when the pull on the cables 62 is decreased by rotating the drum 105 57 in the opposite direction until the tension in the cables is the same as previously, the walking beam and its counterweight are 110 restored to their previous position, thereby elevating the load on the walking beam. In other words, by pulling in on these cables, the vertically movable parts including the 115 ingot gripping mechanism and the work supported by it are lowered in precisely the same way as they would be, should the front end of the walking beam be pulled downward, or should the rear end of the walking beam be pulled upward, by cables connected thereto, and by winding mechanisms supported wholly independently of the walking beam. This also is mentioned for the 120 reason that some such equivalent means for 125

rocking the walking beam may be employed instead of that shown.

In the use of the manipulator, when an ingot of certain size and weight is supported by the gripping unit, the counterweight will be caused to travel back along the walking beam until the walking beam and counterweight overbalance the load supported by the walking beam, and the ingot can be supported at any given elevation, which will usually depend upon the height of the lower die of the forging press, by suitably adjusting the tension of the cables 62. When once the counterweight has been adjusted for a given load to conserve power of operation, it is usually unnecessary to alter its position until the weight of the load is changed by the manipulator taking up an ingot of some different weight, and when the ingot is being forged in the press, as the upper die is lowered, the ingot, and in fact, the entire mechanism connected to the walking beam may move downward, the walking beam swinging on its pivot to accommodate this movement, but as soon as the pressure created by the upper die is removed, the load on the walking beam will immediately move upward to its previous position, this being caused by the unbalanced weight of the counterweight.

Thus by the parallel link connection between the gripping unit and the casting in which it is supported, and by reason of the fact that the entire load, including the ingot, gripping unit, and the parts in which the gripping unit is mounted and supported are yieldingly supported by the walking beam and its counterweight so that they may yield under the action of the dies of the press, no undue stresses are transmitted to the relatively stationary parts of the carriage. At the same time the ingot can be lowered or elevated as may be necessary in transmitting it from one point to another, as for example, from the heating furnace to the press by pulling in or paying out the cable 62, the ingot and the parts associated with it being lowered on pulling in the cables 62, and being automatically elevated by the unbalanced weight of the walking beam and its counterweight as the cables 62 are paid out, or as the tension thereof is decreased.

We have illustrated simply the preferred construction wherein the gripping unit or ram is suspended by the parallel links, and is bodily movable in a vertical direction. However, we do not wish our invention confined to a construction employing both the link suspension feature and the feature of overbalancing the ram and its load through the medium of a pivoted walking beam or equivalent device, for each of these features could be employed advantageously without the other. Furthermore, we do not regard

it essential as far as the overbalancing feature is concerned, that the ram be raised and lowered bodily, for the ram might be otherwise mounted to permit it and its load to be normally overbalanced, and to permit the load to be raised and lowered.

Having described our invention, we claim:

1. In a manipulator, a movable member or carriage, a gripping unit comprising gripping members and a supporting portion extending rearwardly therefrom, and supporting means for the gripping unit including a plurality of links on the lower ends of which the gripping unit is hung from the carriage, said links being spaced lengthwise of the supporting portion, said links being capable of a swinging movement to permit a yielding of the gripping unit in an endwise direction.

2. In a manipulator, a movable frame or carriage, a gripping unit, a supporting member for the gripping unit mounted for vertical movement in the frame or carriage, and a plurality of links each connected at their upper ends to the supporting member and at their lower ends to the gripping unit, said links being spaced longitudinally with respect to the longitudinal axis of the gripping unit and capable of swinging in planes parallel to the longitudinal axis of the gripping unit.

3. In a manipulator, a movable frame or carriage, a gripping unit comprising a spindle rotatable about its axis, and carrying gripping members, spaced bearing members in which the spindle is journaled, and means for supporting said bearing members comprising a vertically movable part carried by the frame or carriage, and two sets of links, each connected to one of said vertically movable parts and to said bearing members, said links capable of swinging in planes parallel to the axis of the spindle.

4. In a manipulator, a movable frame or carriage, a gripping unit, means for movably supporting the gripping unit comprising a walking beam pivoted intermediate its ends to the carriage having a supporting connection with the gripping unit and means for swinging said beam about the pivot to raise or lower the gripping unit.

5. In a manipulator, a movable frame or carriage, a gripping unit, and means for movably supporting the gripping unit comprising a pivoted walking beam movable with the carriage and having a supporting connection with the gripping unit and carrying a counterbalancing weight.

6. In a manipulator, a movable frame or carriage, a gripping unit, and means for movably supporting the gripping unit comprising a pivoted walking beam movable with the carriage and having a supporting connection with the gripping unit and carry-

ing a counterbalancing weight adjustable longitudinally thereof.

7. In a manipulator, a movable frame or carriage, a gripping unit movably mounted so that the work or load carried by it may be raised and lowered relatively to the frame or carriage, and means for overbalancing the gripping unit and the work carried by it comprising a weighted pivoted member

10 movable with the carriage having a supporting connection with the gripping unit, and means for rocking said member to impart vertical movement to the gripping unit.

8. In a manipulator, a movable frame or carriage, a gripping unit capable of movement in a vertical plane with reference to the frame or carriage, means for supporting the gripping unit comprising a pivoted member movable with the carriage having at 20 one side of its pivotal axis a supporting connection with the gripping unit, and having on the opposite side of its pivotal axis a weight for overbalancing the gripping unit and the load supported by it, and means for 25 overcoming the overbalancing effect of said weight so that the gripping unit may be lowered.

9. In a manipulator, a movable frame or carriage, a gripping unit capable of movement vertically with reference to the frame or carriage, means for supporting the gripping unit comprising a pivoted member movable with the carriage having at one side of its pivotal axis a supporting connection 35 with the gripping unit, and having on the opposite side of its pivotal axis a weight for overbalancing the gripping unit and the load supported by it, means for overcoming the overbalancing effect of said weight so that the gripping unit may be lowered, said last mentioned means comprising a cable connection between said pivoted member and a relatively stationary part, and winding means for the cable.

40 10. In a manipulator, a frame or carriage, a gripping unit movable with the carriage, a weight having a connection with the gripping unit for normally overbalancing the gripping unit and its load, and means for 45 lifting the weight to lower the gripping unit.

11. In a manipulator, a movable frame or carriage, a gripping unit movable with the carriage, means for supporting the gripping unit and its load so that the latter may be moved vertically, comprising a pivoted member having a connection with the gripping unit and having a counterweight movable along the same.

60 12. In a manipulator, a movable frame or carriage, a gripping unit movable with the carriage, means for supporting the gripping unit and its load so that the load may be moved vertically, comprising a walking beam having a connection with the gripping

unit, a counterweight on the walking beam, and means for shifting it lengthwise thereof.

13. In a manipulator, a movable frame or carriage, a gripping unit movable with the carriage, means for supporting the gripping unit and its load so that the load may be moved vertically, comprising a pivoted walking beam having a connection with the gripping unit, a counterweight on the walking beam, and means for rocking the walking beam to overcome the overbalancing effect of the walking beam and its counterweight on the gripping unit.

14. In a manipulator, a movable frame or carriage, a gripping unit movable with the carriage, means for supporting the gripping unit and its load so that the latter may be moved vertically, comprising a pivoted walking beam having an operative connection with the gripping unit, and having a carriage movable lengthwise thereof and serving as a counterweight to overbalance the gripping unit and its load.

15. In a manipulator, a movable frame or carriage, a gripping unit movable with the carriage, means for yieldingly supporting the gripping unit and its load so that the latter may be moved vertically, comprising a pivoted walking beam having an operative supporting connection with the gripping unit, and having a carriage movable lengthwise thereof and serving as a counterweight to overbalance the gripping unit and its load, and means for shifting the carriage along the walking beam.

16. In a manipulator, a movable frame or carriage, a gripping unit movable with the carriage, means for yieldingly supporting the gripping unit and its load so that the latter may be moved vertically, comprising a pivoted walking beam having an operative supporting connection with the gripping unit, and having a carriage movable lengthwise thereof and serving as a counterweight to overbalance the gripping unit and its load, and means carried by the carriage of the walking beam for causing it to travel lengthwise of the latter.

17. In a manipulator, a movable frame, a gripping unit movable with the carriage, means for supporting it comprising a pivoted walking beam having a connection with the gripping unit and provided with a carriage which is movable along the walking beam and serves as a counterweight to overbalance the weight of the gripping unit and its load, and means for overcoming the overbalancing effect of the walking beam and the carriage to lower the gripping unit.

In testimony whereof we hereunto affix our signatures.

IVOR D. THOMAS.
PAUL H. DOUGLAS.
